UNITED STATES PATENT OFFICE.

OLIVER J. WARREN, OF DES MOINES, IOWA.

IMPROVEMENT IN CORN-HUSKING IMPLEMENTS.

Specification forming part of Letters Patent No. 136,194, dated February 25, 1873.

To all whom it may concern:

Be it known that I, OLIVER J. WARREN, of Des Moines, in the county of Polk and State of Iowa, have invented a new Corn-Husker, of which the following is a specification:

My invention consists in forming a corn-husker in two parts, one to pass through the hand, similar to a husking-pin, and the other to be worn like a thumb-stall. The part in the hand has a concave spoon-shaped jaw, and the part on the thumb has a corresponding convex jaw with a tooth at the point. They are constructed and co-operated as hereinafter fully set forth.

My drawing is a full-sized perspective view of my husker properly adjusted on a hand, and illustrates its form and the manner of its operation.

A A represent the husking-pin with a spoon-shaped jaw at the upper end. The lower end is pointed. It may be made of cast metal or any other suitable material, complete in one piece, and vary in size to suit large and small hands. Loops or strings may be attached in any suitable way to secure it to the fingers. B B represent the thumb-stall part in the form of a tube made of sheet metal. C is the convex jaw corresponding in form with the concave spoon-shaped jaw on the end of A A. It closes the front end of the tube B, and is permanently joined thereto in any suitable way. It extends below the tube and terminates in a narrow end, which is curved upward and attached to the under side and rear end of the tube. a is a metal hook or tooth securely attached at the junction of the front and upper points of the tube B and jaw C, and extends downward

over the point of the lower or concave jaw. b b represents a strap or cord passed between the curved end of the jaw C and the tube B, and tied around the thumb and wrist to prevent the thumb-stall part from flying off in the act of throwing the husked corn.

The parts B, C, and a may be cast together complete in one piece, and, by making the tube B short, a leather or flexible thumb-stall may be used in place of the long rigid tube.

The husking-pin part A A may be used independent of the other part, and with equal advantage to any other husking-pin. But my improvement consists in adapting the two separate parts to co-operate so that the husks can be torn open and seized between the jaws and stripped from the corn without coming in contact with the thumb and fingers, and consequently without wearing and bruising the skin and flesh. The point of the lower jaw can be run into the husk the same as any husking-pin. The tooth on the upper jaw can also be pressed into the husk. A double hold is thus secured, and when the jaws are pressed together it is immaterial whether the arm is moved up or down, or to or from the operator. The husk can be pulled in either of those directions with equal facility.

Claim.

I claim as my invention—
A corn-husker, composed of the parts A, B, C, and a, substantially as described.

OLIVER J. WARREN.
